ELECTRIC SWITCH

John R. Caldwell, Hampton, Olan Richardson,
Atlanta, and Thomas E. Curtis, Hampton, Ga.,
assignors to Southern States Equipment Cor-
poration, a corporation of Georgia

Application January 10, 1947, Serial No. 721,184

3 Claims. (Cl. 200—48)

1

This invention relates to electric switches in which a hingedly mounted switch arm is moved into and out of engagement with a contact spaced away from the hinge mounting, and in which the pressure between the switch arm and the contact is increased after the switch arm has completed its arcuate motion in closing. More particularly it relates to the type of switch in which this increased pressure is produced by a partial rotation of the switch arm about its longitudinal axis.

Referring to the drawings, Fig. 1 shows in reduced scale a single pole of one type of switch embodying this invention; Fig. 2 is an enlarged side view of the hinge portions of the switch; Fig. 3 is a top view of the parts shown in Fig. 2; Fig. 4 is a sectional view along the plane 4—4 when the switch arm is midway in its rotative travel; Fig. 5 is a longitudinal view along the section 5—5; Fig. 6 is an end view of the switch arm and the contact; Fig. 7 is a diagram explaining one part of the operating motions of the switch; Fig. 8 is a top view of a modified arrangement of the operating member; and Fig. 9 shows a detail.

The base 1 supports two stationary insulators 2, 3 and one rotative insulator 4 which is controlled by crank 5. The crank 6 is integral with the rotative insulator unit 4. The hinge base 7 is secured to insulator 3 and it also serves as a steady bearing for the top of insulator unit 4. Line 8 is connected to hinge base 7, and line 8' is electrically connected to contact 13. Switch-arm structure 9 is hinged on hinge pivot 10 and it includes the switch arm 11 which is rotative about its own longitudinal axis. Switch arm 11 has a flattened end 12 which engages with contact 13. Rocker 14 is mounted on hinge base 7 by rocker pivot 15 which is parallel with hinge pivot 10, connecting rod 16 is held by a universal joint to crank 6, and a second universal joint and swing pivot 17 hold connecting rod 16 to rocker 14. Swing pivot 17 also carries two curved links 18, 19 which are connected by diagonal pivot 20 to terminal bearing member 21 which is integral with and a part of rotative switch arm 11. The switch-arm structure 9 also includes the hinge member 22 which is mounted on the hinge base 7 by hinge pivots 10, 10', and which provides the trunnion in which terminal bearing member 21 rotates.

Fig. 7 is a diagram showing how switch arm 11 is rotated by motion of rocker 14 and links 18, 19. When the switch is fully closed swing pivot 17 is at position indicated by 17a and the

2

link 19 is indicated by 19a, with the near end of diagonal pivot 20 being at a. The location of rocker pivot 15 is shown at 15a. Link 18 occupies the position indicated by 18a, with the far end of pivot 20 being at location c. As rocker 14 is moved so that swing pivot 17 is moved to position 17b, the link 18 takes position 18b and link 19 takes position 19b. In other words the near end of pivot 20 is raised to b and the far end of pivot 20 is lowered to d. This places link 19 in tension and link 18 in compression and as they are on opposite sides of switch arm 11 they rotate switch arm 11 without otherwise changing its location. Fig. 8 is a plan view showing how the two links 18, 19 can be replaced by a single bifurcated member 23 which is mounted on diagonal pivot 20 and on swing pivot 17 without altering the locations of said pivots. In this case swing pivot 17 passes through the single eye 24 which is integral with 23, and which fits within the clevis 25, which is part of the universal joint connection to connecting rod 16. In this case, the single 23, 24, 25 is rotatable about the straight diagonal pivot 20, the eye 24 tending to move at right angles to axis of pivot 20. However, the rocker 14 forces swing pivot 17 to travel at right angles to axis of pivot 15. The resultant is the same as with two separate links, namely to raise one end of pivot 20 and lower the other end, thereby causing rotation of switch arm 11. There are slight discrepancies in the travel of the various members, and when two links such as 18, 19 are used, proper clearances are allowed at each end of each link to prevent binding. When a single bifurcated link is used such as 23, 24, 25 all the clearance for these slight discrepancies is provided between eye 24, clevis 25 and swing pivot 17. As shown in Fig. 9, the link 23, 24, 25 may be replaced by the swivelled members 23', 24', 24'' the swivelled eye 24' replacing the rigid eye 24. In such arrangements, no extra clearance is needed between eye 24' and clevis 25.

Operation is as follows: Assuming the switch to be fully closed, the flat end 12 of arm 11 is horizontal and is in heavy pressure engagement with contact members 13, 13. Hinge members are as shown in Fig. 2. When crank 5 is turned, connecting rod 16 moves rocker 14 counter-clockwise moving swing pivot 17 from position 17a to 17b. This places link 19 under tension and link 18 under compression. This partially rotates switch arm 11 so that end 12 is released from heavy pressure against contact 13, 13. Further motion of crank 5 moves pivot 17 so that the

plane which includes the axes of pivots 17 and 15 is past the locations c and d. Further counter-clockwise motion of rocker 14 changes the stress on link 18 from compression to tension so that links 18 and 19 are both in tension and this lifts the diagonal pivot 20 and so raises switch arm 11 through its operating plane, which is normal to the axis of pivots 10, 10', until the switch arm ultimately reaches its fully open vertical position. Since the axes of pivots 10, 10' and 15 are parallel, the motion of swing pivot 17 is likewise parallel with the operating plane through which switch arm 11 swings.

The reverse motions close the switch and rotate arm 11 so that end 12 is again horizontal as shown in Fig. 6 and the switch is fully closed.

If it should be desired, diagonal pivot 20 could be replaced by two separate pivots which need not have the same axes. Instead of pivot 17 serving as the connection with connecting rod 16, a second pivot could be provided adjacent to pivot 17. And various other changes might be made by one familiar with the art without departing from the spirit and purpose of this invention.

We claim:

1. In an electric switch, an insulated contact, and spaced away from it an insulated hinge base carrying a hinge pivot, a switch arm mounted on said hinge pivot to swing through its operating plane from its open position to its closed switch location and into engagement with said contact and also rotatable about its longitudinal axis when at its closed location, a rocker pivot mounted in a fixed position on said hinge base spaced from and parallel with said hinge pivot, a rocker mounted on said rocker pivot, a swing pivot in the swing end of said rocker and movable only in a fixed arc parallel with said operating plane, and linkage directly connecting the swing pivot with the rotatable switch arm to rotate the switch arm when at its closed location, together with means to move the rocker in one continuous motion and so operate the switch from fully closed to fully open position.

2. In an electric switch an insulated contact and spaced away from it an insulated hinge base carrying a hinge pivot, a switch arm mounted

on said hinge pivot to swing in its operating plane into and out of engagement with said contact and also rotatable about its own longitudinal axis when at its closed switch location, a rocker pivot

5 also mounted on said hinge base and a rocker mounted on said rocker pivot, with its swing end movable only in a fixed arc about the rocker pivot and parallel with said operating plane, two links pivotally connected to the swing end of the rocker and with their other ends pivotally connected with the rotatable switch arm at substantially different distances from the hinge pivot and operable by motion of the rocker to rotate the switch arm about its longitudinal axis when the switch arm is at its closed location.

3. In an electric switch, an insulated contact and in spaced relation to it an insulated hinge base carrying a hinge pivot, a switch arm mounted on said hinge pivot to swing in its operating plane from its open position to its closed switch location and into engagement with said contact and also rotatable about its own longitudinal axis to vary its engagement pressure with said contact, a swing pivot movably supported upon said hinge base and movable only in a fixed arc parallel with said operating plane, two links pivotally connected with said swing pivot and with their other ends pivotally connected to opposite sides of said switch arm at substantially different distances from said hinge pivot and operable to rotate the switch arm when at its closed location, together with operating members to move the swing pivot and thereby to operate the switch.
